[57] CLAIM

The ornamental design for a pet leash, as shown and described.

DESCRIPTION

FIG. 1 is an isometric view a pet leash showing my new design;

FIG. 2 is an isometric view of the wrist strap portion of the pet leash of FIG. 1 as seen from the side opposite that shown in FIG. 1, the remaining portion not shown being identical to that portion seen in FIG. 1;

FIG. 3 is an isometric view of a second embodiment of the pet leash showing my new design;

FIG. 4 is an isometric view of the wrist strap portion of the second embodiment as seen from the side opposite that shown in FIG. 3, the remaining portion not shown being identical to that portion seen in FIG. 3;

FIG. 5 is an isometric view of a third embodiment of the pet leash showing my new design; and,

FIG. 6 is an isometric view of the wrist strap portion of the third embodiment as seen from the side opposite that shown in FIG. 5, the remaining portion not shown being identical to that portion seen in FIG. 5.
